Patented Feb. 10, 1976

238,763

SNOWMOBILE ENGINE COWLING

Edwin B. Hatch, West Bend, Wis., assignor to
Brunswick Corporation, Skokie, Ill.

Filed Mar. 13, 1974, Ser. No. 450,663

Term of patent 14 years

Int. Cl. D12—14

U.S. Cl. D12—7

Fig. 1

Fig. 2

Fig.3

Fig.4

Fig. 5

FIG. 1 is a perspective view from the front and one side of a snowmobile engine cowling showing my new design;

FIG. 2 is a side elevational view thereof, it being understood that the opposite side is a mirror image of the side shown herein;

FIG. 3 is a front elevational view thereof;

FIG. 4 is a rear elevational view thereof; and

FIG. 5 is a top plan view thereof to an enlarged scale.

I claim:

The ornamental design for a snowmobile engine cowling, substantially as shown and described.
